To all whom it may concern:

Be it known that I, AUSTIN F. The figure is a front face or upper side view of a coffee-spoon having my design applied to it.

The leading feature of my design is a representation of a violet-blossom *a*, applied to

and forming the extreme end of the handle, the outer edges of the petals forming the marginal edge of the handle and imparting their shape to the same. Below the blossom there are two leaves *b*, rising from a point below on the handle and encircled at such point by an ornamental band *c*.

What I claim is—

The design for a spoon-handle, as herein shown and described.
